(57) **CLAIM**

The ornamental design for an identification tag for biological and pharmaceutical applications, as shown and described.

DESCRIPTION

FIG. 1 is a front perspective view of an identification tag for biological and pharmaceutical applications, according to an embodiment;

FIG. 2 is a front view of the identification tag for biological and pharmaceutical applications illustrated in FIG. 1;

FIG. 3 is a rear view of the identification tag for biological and pharmaceutical applications illustrated in FIG. 1;

FIG. 4 is a left side view of the identification tag for biological and pharmaceutical applications illustrated in FIG. 1;

FIG. 5 is a right side view of the identification tag for biological and pharmaceutical applications illustrated in FIG. 1;

FIG. 6 is a top view of the identification tag for biological and pharmaceutical applications illustrated in FIG. 1; and, FIG. 7 is a bottom view of the identification tag for biological and pharmaceutical applications illustrated in FIG. 1. The broken lines in the figures show portions of the identification tag for biological and pharmaceutical applications that form no part of the claimed design.

1 Claim, 5 Drawing Sheets
